UNITED STATES PATENT OFFICE.

OTHO C. DURYEA, OF LOS ANGELES, CALIFORNIA, ASSIGNOR TO NATIONAL GAS DRILL CO., OF LOS ANGELES, CALIFORNIA, A CORPORATION OF CALIFORNIA.

MEANS FOR CIRCULATING A COOLING MEDIUM IN GAS-ACTUATED ROCK-DRILLS.

No. 846,407.

Specification of Letters Patent.

Patented March 5, 1907.

Application filed December 11, 1905. Serial No. 291,218.

To all whom it may concern:

Be it known that I, OTHO C. DURYEA, a citizen of the United States, residing at Los Angeles, in the county of Los Angeles and State of California, have invented a new and useful Means for Circulating a Cooling Medium in Gas-Actuated Rock-Drills, of which the following is a specification.

The object of this invention is to provide a free-piston gas-actuated rock-drill with cooling-fluid-circulating means arranged in effective, simple, compact, convenient, and durable form.

The accompanying drawings illustrate the invention.

Figure 1 is a side elevation of a free-piston gas-actuated drill in which this invention is applied. The piston is shown at the close of its pump-actuating stroke. A fragment of the drill-steel is shown. Fig. 2 is a fragmental axial section on line $x^2 x^2$, Fig. 3, the parts being in position at the close of the return stroke of the pump. The piston is not sectioned. Fig. 3 is a front view with the piston-rod of the drill in cross-section on line $x^3 x^3$, Fig. 2.

1 designates a free-piston gas-actuated drill provided in its cylinder 2 with a passage 3 for a medium for cooling the cylinder and also provided with a piston 4, having an inclined face in the form of a taper portion 5 on its rod 6.

7 is a pump for circulating water or other cooling medium through said passage 3, and 8 designates pump-actuating means in the form of a pivoted bell-crank attached to the cylinder by means of a frame 9, screwed on the end of the cylinder 2. The bell-crank 8 is provided with a roller 10 to engage the taper portion 5 of the piston-rod to thereby be actuated, said actuation being direct on the pumping stroke and through a spring on the return stroke. The face of the roller 10 is preferably concave to approximately fit the convexity of the taper portion 5 of the piston 4.

11 is the pump-piston actuated by roller 12 on one arm 13 of the bell-crank 8.

14 designates yielding means in the form of a spring for returning the pump-piston as the taper portion of the drill-piston withdraws from the bell-crank. In the drawings the only part of the drill-piston shown is a portion of the piston-rod with drill-chuck

attached thereto; but it is to be understood that the piston is provided with a suitable head or heads (not shown) by which said rod is actuated.

In practical operation the taper portion of the reciprocating piston will operate the bell-crank, thus operating the pump-piston in one direction against the force of the spring 14, which returns the pump-piston as the drill-piston moves to relieve the bell-crank.

15 indicates hose connections for returning the cooling medium to and drawing it from a suitable tank 16.

17 and 18 are respectively the receiving and discharging checks of the pump.

It is to be understood that where the piston-rod carries the drill-steel 19 and is rotated for rotating the steel the slanting or inclined face which actuates the pump through the means of the bell-crank is of taper form, and the piston-engaging roller 10 on the bell-crank is preferably concave, as shown: but if the piston-rod is not made to rotate the inclined face 5 may be flat or otherwise formed. The roller may in any case be made in the form deemed best for the purpose. I do not limit the invention to the exact construction shown.

20 designates a stud screwed into the cylinder 2 to act as a stop for the check-valve 18 and as a guide for the check-spring 21.

22 designates bolts detachably securing the pump to the cylinder 2. The pump-piston 11 is chambered to receive the return-spring 14, and the stud 23 for said spring is riveted in such piston.

What I claim is—

1. In a gas-actuated rock-drill, a cylinder, a pump for circulating a cooling medium therethrough, and a piston for said cylinder provided with a taper portion for operating the pump.

2. In a gas-actuated rock-drill, the combination with a cylinder having a passage for a cooling medium, of a pump-cylinder communicating with such passage, a piston for the pump-cylinder, means for actuating the same, and a piston for the rock-drill having a slanting face for operating said actuating means.

3. In a rock-drill, a piston having a slanting face, a pump for circulating a medium for cooling the cylinder of the rock-drill, a bell-

crank arranged to be operated by the slanting face and to operate the pump, and yielding means for holding the pump-piston in position for engagement with the bell-crank.

5 4. In a rock-drill, a piston having a slanting face, a pump for circulating a medium for cooling the cylinder of the rock-drill, a bell-crank detached from the pistons and arranged to be operated by the slanting face
10 and to operate the pump, and yielding means

for holding the pump-piston in position for engagement with the bell-crank.

In testimony whereof I have hereunto set my hand, at Los Angeles, California, this 1st day of December, 1905.

OTHO C. DURYEA.

In presence of—

JAMES R. TOWNSEND,
TILLIE E. ADAM.
